CLAIM

The ornamental design for a connector interface for a cable, as shown and described.

DESCRIPTION

FIG. 1 is a perspective view of a first embodiment of a connector interface for a cable of my new design.

FIG. 2 is a second perspective view thereof.

FIG. 3 is a third perspective view thereof.

FIG. 4 is a perspective view of a second embodiment of a connector interface for a cable of my new design.

FIG. 5 is a second perspective view thereof; and,

FIG. 6 is a third perspective view thereof.

The broken line showing of a connector interface for a cable represents unclaimed subject matter and forms no part of the claimed design.

1 Claim, 4 Drawing Sheets

FIG. 3

FIG. 6
